A roof truss forming machine for assembling and nailing with nail plates timbers into a planar roof truss includes a stationary elongated track and a plurality of adjustably positioned support arms extending laterally therefrom and pivotally secured thereto. Each of said support arms having at least one clamping device adjustably positioned thereon each of said clamping devices incorporating a hydraulically operated C-clamp for pressing the nail plates into the timbers supported by the devices.

FIG. 4

ROOF TRUSS FORMING MACHINE

BACKGROUND OF THE INVENTION

1. Field of the Invention

This invention relates to roof truss forming machines of the type used for assembling wood frames such as roof trusses made of wood elements abutted together and secured by spiked truss connector plates wherein the components of the machine are movable relative to one another so as to accommodate various sizes and shapes of roof trusses to be formed.

2. Description of the Prior Art

Structures of this type have usually employed a stationary elongated rail with a plurality of bridges or support arms extending laterally therefrom with the actual clamping devices located along the rail and on the bridges or support arms. (See U.S. Pats. Nos. 3,530,790, 3,487,430, 3,255,943, 3,069,684 and 3,068,484. Other prior art devices wherein the clamping stations are independent of the base rail construction are illustrated in U.S. Pats. Nos. 3,358,348 and 3,487,430. This invention eliminates the problems heretofore experienced in adjusting the machine to a particular size and angular configuration of a roof truss to be formed by pivoting the support arms to the fixed longitudinal track so as to enable the same to be moved longitudinally of the track and at the same time moved in an arc based on their pivotal attachment to the track thus permitting the clamping stations with their hydraulically actuated C-clamps to be positioned in any conceivable configuration in which the wooden members forming the roof truss require attachment to one another.

SUMMARY OF THE INVENTION

A roof truss forming machine comprises a base track having a plurality of support arms adjustably attached thereto and including pivot means permitting the support arms to be moved in an arc based on such means. Clamping stations incorporating hydraulically actuated C-clamps are adjustably positioned on the support arms so that by arranging the support arms in desired position along the base track and at a desired angular relation with respect thereto, the clamping stations may be readily and easily positioned to secure nail plates to the timbers being joined thereby to form a roof truss.

DESCRIPTION OF THE DRAWINGS

FIG. 1 is a top plan view of the roof truss forming machine.

FIG. 2 is an enlarged side elevational view of a portion of the machine on line 2-2 of FIG. 1.

FIG. 3 is a top plan view on line 3-3 of FIG. 2.

FIG. 4 is a vertical section on line 4-4 of FIG. 2 and

FIG. 5 is a vertical section on line 5-5 of FIG. 2.

DESCRIPTION OF THE PREFERRED EMBODIMENT

In its preferred form the roof truss forming machine of this invention is comprised of a stationary base track 10 formed of a pair of I-beams 11 having support bases 12 with adjustment members 13 provided for leveling the same with respect to a supporting surface and as best seen in FIG. 2 of the drawings.

By referring now to FIG. 1 of the drawings, it will be seen that the stationary base track 10 is of a length greater than the span of a truss to be formed thereon, said truss being indicated in outline in broken lines 14

in FIG. 1. A plurality of support arms 15 are pivotally attached at their one end, the lower end, as seen in FIG. 1 of the drawings and their left end as seen in FIG. 2 of the drawings by pivots 16 which engage carriages 17 which in turn are provided with wheels 18 traveling on the I-beams 11 of the base track 10.

By referring now to FIGS. 1 and 2 of the drawings it will be seen that each of the plurality of support arms 15 extend generally perpendicularly to the base track 10 and are movable in arcs based on the pivots 16. The outer ends of each of the support arms 15 are provided with wheels 19 to facilitate the arcuate movement thereof relative to their pivotal attachment to the base track 10. In FIG. 5 of the drawings, a cross sectional detail of one of the support arms 15 may be seen together with the representation of the support wheel 19 on the outer end thereof.

In FIG. 4 of the drawings, a cross section taken through the carriage 17 and the pivot 16 illustrate the side view of the carriage 17 and its positioning on the base track 10 and specifically the I-beams 11 thereof.

By referring to FIG. 3 of the drawings, it will be observed that each of the support arms 15 is largely formed of a pair of secondary I-beams 20 the upper surfaces of which are flat as also seen in FIG. 2 of the drawings and by referring thereto it will be observed that an adjustable, slideable secondary carriage 21 is positioned thereon for longitudinal movement with respect thereto. The secondary carriage 21 has a rotatable base plate 22 thereon which in turn supports a clamping station which includes a vertical support structure 23 and a hydraulically actuated C-clamp 24. The vertical support structure 22 includes a horizontal surface 25 on which the timbers being formed into a planar roof truss are positioned. It will occur to those skilled in the art that various configurations of C-clamps may be employed with the present invention and that a plurality of such C-clamps as shown in detail in FIG. 2 of the drawings are necessary as seen in FIG. 1 of the drawings wherein a pair of the clamping stations incorporating the C-clamps 24 are positioned on each of the support arms 15 with the exception of the endmost support arms wherein only one of the C-clamps 24 is necessary.

By referring now to FIG. 1 of the drawings, it will be seen that the broken line representation of the outline of a wooden truss 14 shows the same positioned on the horizontal supports 25 of each of the clamping stations and between the jaws of the hydraulically actuated C-clamps 24 and it will further be seen by reason of the adjustability of the positions of the support arms 15 the clamping stations with their C-clamps 24 may be quickly and easily positioned to join the ends of the web members, not shown, to the straight and angular portions of the roof truss being formed. Thus as many web members positioned at whatever angle is desired or perpendicularly with respect to anyone of the timbers of the truss being formed may be employed and fastened at their end sections to the truss members by the easy and convenient location of the clamping stations made possible by the adjustability of the support arms which carry the same and the fact that each of the clamping stations is rotatable with respect thereto.

Those skilled in the art will understand that the hydraulic C-clamps referred to herein and indicated by the numerals 24 are actually C-shaped jaws movable hydraulically with respect to the horizontal surfaces 25

of the support structures 23 of the clamping stations. In a preferred form of the invention the C-shaped clamping arms 24 of the C-clamps and the horizontal support surfaces 25 or movable portions thereof are movable vertically toward and away from one another. In the preferred form of the invention a remote source of hydraulic fluid under pressure and conduits for conveying the same along the base track 10 and outwardly of each of the support arms 15 will be necessary and in FIG. 2 of the drawings several such tubular conduits are illustrated and generally indicated by the numerals 26.

Although but one embodiment of the present invention has been illustrated and described, it will be apparent to those skilled in the art that various changes and modifications may be made therein without departing from the spirit of the invention.

Having thus described my invention what I claim is:

1. A roof truss forming machine for assembling and nailing with nail plates timbers into a planar roof truss comprising a stationary base track, a plurality of carriages arranged for movement along said base track and a plurality of support arms each of which is pivoted at one of its ends to one of said carriages and positioned laterally with respect thereto and to said base track, wheels on the other end of each of said support arms, a plurality of secondary carriages positioned on said support arms and movable longitudinally thereof, clamping stations adjustably positioned one on each of said secondary carriages, said clamping stations including hydraulically actuated C-clamps and means for supporting said timbers in operative relation thereto and a source of hydraulic pressure for actuating said hydraulic C-clamps.

2. A roof truss forming machine as defined in claim 1 wherein said base track comprises a pair of spaced, parallel elongated members, means interconnecting said members for maintaining said parallel relationship thereof and adjustment means acting to level said base track.

3. A roof truss forming machine as defined in claim 1 and wherein wheels are provided on said plurality of carriages arranged for movement along said base track and means on said carriages engages said base track to maintain said carriages in position thereon.

4. A roof truss forming machine as defined in claim 1 and wherein pivot means engaging said first mentioned carriages and said support arms is arranged to be secured in rotatable and fixed position.

5. A roof truss forming machine as defined in claim 1 and wherein swivel plates are mounted on said first mentioned carriages and said support arms are engaged on said swivel plates.

6. A roof truss forming machine as defined in claim 1 and wherein each of said support arms has a pair of elongated members positioned in spaced parallel relation and wherein said secondary carriages are positioned on said elongated members.

7. A roof truss forming machine as defined in claim 1 and wherein secondary swivel plates are positioned on each of said secondary carriages and said clamping stations are mounted on said secondary swivel plates and means is provided for securing said secondary swivel plates to said carriages in rotatable and fixed relation.
